UNITED STATES PATENT OFFICE

PHILIP J. KROLL, OF PITTSBURGH, PENNSYLVANIA.

ELECTROLYTIC APPARATUS.

1,306,151.

Specification of Letters Patent. Patented June 10, 1919.

Application filed November 5, 1917. Serial No. 200,345.

To all whom it may concern:

Be it known that I, PHILIP J. KROLL, residing at Pittsburgh, in the county of Allegheny and State of Pennsylvania, a citizen of the United States, have invented or discovered certain new and useful Improvements in Electrolytic Apparatus, of which improvement the following is a specification.

10 My invention relates to electrolytic apparatus, and has particularly to do with diaphragm electrolytic apparatus, and has particularly to do with diaphragm electrolytic apparatus for the purpose of decomposing 15 water to produce oxygen and hydrogen gases.

My object is to provide an apparatus for this purpose which will be simple in construction and particularly efficient and effective in operation. A further object is to provide such apparatus with means for limiting the pressure on each side of the diaphragm, and with improved means for washing the gases generated within the apparatus.

In the accompanying sheets of drawings which illustrate the preferred embodiment of my invention, Figure 1 is a side view of an electrolytic cell, portions 30 of the casing thereof being broken away to show the interior construction; Fig. 2 a plan view of an electrolytic apparatus comprising two cells of the character shown in Fig. 1; Fig. 3 a side view of the apparatus shown in Fig. 2; Fig. 4 a sectional view of but one cell taken on the plane indicated by the broken line IV—IV, Fig. 2, the side plates or electrodes and diaphragm parts being separated to more clearly illustrate the construction; Fig. 5 a sectional view to enlarged scale of the gas-washing apparatus, such section being taken on the line V—V, Fig. 2; Fig. 6 a combined side view of the pressure limiting gas-washing 45 apparatus shown in Fig. 5 and detached sectional view to enlarged scale of a portion of the cell; Fig. 7 a combined vertical central sectional view of the water feeder and face view of a portion of the lower edge of 50 the cell; and Fig. 8 a detached plan view showing a detail of construction to which reference is made hereinafter.

My invention may be conveniently described by explaining separately the three 55 main features thereof, namely, the construction of the cell including the electrodes

and diaphragm; the construction of the water-feeding means; and third, the construction of the gas-washing and pressure limiting means.

While as far as some features of my invention are concerned, any suitable form of electrolytic cell may be used, I preferably provide a cell comprising two plate electrodes, 1 and 2, which for simplicity of 60 construction are structurally identical. Thus the same molds may be used for casting each of these plates. The cathode plate is preferably made of iron or at least has an iron inner face, while the inner face of 65 the anode is preferably of any non-corrosive metal. The inner faces of both plates 1 and 2 may in the usual or any desired manner be provided with suitable projections or 70 corrugations for the purpose of increasing the 75 surface area thereof.

Between the electrode plates 1 and 2 there is clamped a diaphragm which forms with such plates electrolyte compartments. The diaphragm preferably consists of a fabric 3 80 of asbestos or other suitable material permeable to the electrolyte, but through which the gases generated in the electrolyte compartments will not pass. This diaphragm is 85 stretched over and secured to a rigid frame 4 of the same shape as the outer edges of the plates 1 and 2. Surrounding the frame 4 there is peripheral frame 35 adapted to prevent the escape from the cell of the electrolyte by reason of the capillary action of the 90 diaphragm upon the electrolyte. The frame 35 may be made of hard rubber, steel or other rigid material. At each side of the frame 35 there is an insulating frame 5 of the same 95 shape as the frame 35. The several frames are held in position within the cell by means 100 of clamping members, such as the bolts 36 for attaching the plates 1 and 2 of each cell to each other. If desired, each plate may have a foot 39 connected to it by means of an electrically insulated joint, each foot having a glass base 40. It will be observed of the specific cell construction thus far described that it may be easily assembled and may be as readily disassembled, when necessary for purposes of cleaning or repair.

The cell may be used singly or several cells may be combined into a single electrolytic apparatus. When so combined the apparatus consists of a plurality of bi-polar 111 cells, each cell or unit being connected to the adjacent cell without an intervening neutral,

so that the cathode plate of one cell is adjacent to the anode plate of the other cell. The mechanical or structural connection of adjacent cells to each other is preferably of such a character that it affords electrical continuity from the anode plate of one cell to the cathode of the adjacent cell. While various means may be provided for thus connecting the cells to each other, each electrode plate is, as particularly indicated in Fig. 8, preferably provided at its central portion with a laterally projecting wedge-shaped lug 6, and a pair of recessed clamping bars 7 are placed one on each side of the adjacent contacting lugs, and brought into firm wedging engagement therewith, as by means of suitable bolts 8. Thus, each cell may be separately assembled, and in assembled form be readily connected to another assembled cell, the mechanical connection affording good electrical conductivity between adjacent cell plates.

Turning now to the second feature of my invention, which has to do with feeding water to the electrolyte compartments of the cell, the water is preferably fed to the bottom of each compartment by means of communicating conduits so constructed that the gas generated in one cannot pass into the other compartment.

In the illustrative embodiment of this feature of my invention, the bottom portion of each plate 1 and 2 is provided with a water inlet supply port 9 which port communicates with a downwardly extending passageway 10 formed integrally with such plates. A U-shaped conduit 12 is mechanically connected at one end to the lower end of each passageway 10, the other ends of these U-shaped conduits combine at their upwardly extending ends into a single conduit 13, it being observed that the adjacent U-shaped conduits are separated by means of a vertically extending baffle 14. The single conduit portion 15 is connected to a single vertically disposed conduit 15 to the upper end of which is attached a suitable reservoir 16 for supplying water. By this arrangement, feed water may be placed in the reservoir 16 and, flowing through the conduit 15, be divided into two streams by the baffle 14, which streams flow through the U-shaped conduits 12 and passageways 10 into the electrolyte chambers formed on opposite sides of the diaphragm 3. If, by reason of some abnormal exterior condition, the pressure within one electrolyte chamber becomes materially greater than that in the other, with the result that the electrolyte from the high pressure chamber is forced therefrom into the low pressure electrolyte chamber, the gas generated within one chamber cannot, by reason of the baffle plate 14, pass into the other chamber. With respect to this, it will be understood that such

gas as may be carried with the electrolyte as it flows from one toward the other compartment, will be vented into the conduit 15 and reservoir 16 which is open to the atmosphere.

Coming now to the third feature of my invention, namely, the means for washing the gas generated by and within the electrolytic cell, means are provided whereby an excess volume of the washing fluid may be carried to the electrolyte chambers of the cell. With respect to this, it will be understood that the gases issuing from the electrolyte cells carry with them a certain amount of moisture sometimes in the form of foam, and that this moisture or foam being taken up by the washing fluid gradually increases the volume thereof. The moisture or foam thus deposited in the washing fluid contains appreciable amounts of whatever substance may be mixed with the water in the cell to render such water conductive, such substance for example being acid or a base such as soda or potash. Thus by returning this excess volume of water in the gas-washing chamber, these electrolyte substances are conserved.

In the illustrative embodiment of this feature of my invention, the upper portion of each plate 1 and 2 is provided with a port 17, through which gas passes from the electrolyte chamber, and with a port 18 through which excess washing water may be returned thereto. A gas-washing casing 19, provided with ports 37 and 38, is secured to each plate 1 and 2, the ports 37 and 38 registering, respectively, with the ports 17 and 18, a suitable insulation gasket being placed between the plates and the casing.

Referring particularly to Figs. 5 and 6, the casing 19 may be provided with a passageway 21 in which, if desired, there may be arranged a plurality of baffle plates 22 for effecting a partial separation of the gas from the foam or moisture carried thereby. Communicating with the upper portion of the passageway 21 there is a passageway 23 adapted to carry the gases downwardly within the body of washing fluid 24, which is preferably water. The body of water 24 is contained within communicating chambers formed by a partition 25 projecting downwardly from the top of the casing to a point adjacent the bottom thereof. The gases, after passing through the body of water 24, flow upwardly through the passageway 26 formed in the casing 19 and from thence to a suitable bell or other container not shown herein, the construction of which is well understood by those skilled in the art. The upper end of the chamber 27, which also contains water in communication with the body 24 thereof, is preferably exposed to atmospheric pressure so that the level of the water in the chamber 27 is above that of the body 130

24 due to the pressure of the gas in the bell or container. As the volume of water increases, due to the absorption of vapor or foam carried by the gases, the level of the 5 water in the chamber 27 will rise until it reaches the top of a partition 28, over which partition it may flow into a passageway 29 and from thence through a trap 30 and ports 38 and 18 into an electrolyte chamber. It 10 will be observed that the gas washers are identical for the electrolyte compartments of each cell. As a consequence thereof, the pressure of each compartment of each cell is independently regulated, such regulation 15 being effective by reason of the fact that each compartment is, through ports 18 and 38, trap 30 and passageway 29, exposed to the atmosphere.

Since the operations of the several 20 features of my invention have been severally explained in connection with the descriptions thereof, it seems unnecessary to repeat the explanations thereof.

According to the provisions of the patent 25 statute, I have described the principle and operation of my invention, together with the construction which I now consider to represent the best embodiment thereof. However, I desire to have it understood that my 30 invention may be practised by other forms of construction than that particularly shown and described herein.

I claim as my invention:

1. In an electrolytic apparatus, the combination of a plurality of cell units, each including a pair of separate plates forming electrodes, said plates being insulated from each other and in the assembly of the apparatus being arranged side by side, and means 35 between each pair of adjacent cell units for detachably connecting both structurally and electrically the anode plate of one cell unit to the cathode plate of an adjacent cell unit, whereby each unit may be separately detached from the assembly of units.

2. In an electrolytic apparatus, the combination of a pair of cells each including a pair of plate electrodes, the central portions of each plate having laterally projecting 40 lugs formed integrally therewith, and means 50 for connecting through said lugs a cathode

and anode plate to each other, said connection affording electrical continuity between the connected plates.

3. In an electrolytic apparatus, the combination of a pair of cells each including a pair of separate plates forming electrodes, the central portion of each plate having formed integrally therewith a laterally projecting wedge-shaped lug, and a clamp engaging the lugs of a cathode and anode plate, of each cell.

4. In an electrolytic cell, the combination with a casing provided with a diaphragm separating such casing into two electrolyte compartments, the bottom portion of the casing being provided with fluid supply ports communicating one with each compartment, a separate electrolyte supply conduit leading downwardly and then upwardly from each of said ports and a single conduit connected to the upwardly turned ends of said two conduits.

5. In an electrolytic cell, the combination of a pair of plate electrodes connected to each other, a diaphragm between said plates and forming therewith a pair of electrolyte compartments, the bottom portion of each plate being provided with a fluid supply port, U-shaped conduits each having one end communicating with one of said ports, and a single fluid supply conduit connected to the other upwardly turned ends of said conduits.

6. The combination with an electrolytic cell for the decomposition of water, of a gas washer comprising a casing provided with a partition extending from the top to a point adjacent to the bottom thereof and forming with said casing water containing chambers, communicating at their lower ends, said casing being provided with a passageway for carrying gas into the body of water in one of said chambers, and with a second passageway for carrying accumulated excess water from the top of the other of said 90 chambers to the cell.

In testimony whereof I have hereunto set my hand.

PHILIP J. KROLL.
